SURGICAL SUPPORT

Ariel M. Le May, Chicago, Ill., assignor to S. H.
Camp & Company, Jackson, Mich., a corpora-
tion of Michigan

Application December 14, 1932, Serial No. 647,165

8 Claims. (Cl. 2—41)

The present invention relates to surgical garments and has particular reference to supports and belts capable of correcting entroptosis and gastroptosis conditions.

5 As a primary object, this invention provides a surgical garment having an occupancy surface which is adapted to be positioned inwardly of the plane of the iliac crest to hug closely the abdominal wall thus providing a supporting shelf normally positioning ptoed organs.

10 Another object of this invention is to provide an occupancy surface which is anchored snugly against the abdominal walls through the employment of retaining side sections effective above 15 and below the iliac crests and free from any interference thereby.

15 A further object of the invention is to provide an abdominal support for positioning ptoed organs in which iliac crest pressure or interference is eliminated through the employment of 20 specific type of hood or pocket.

25 These and other objects will appear in the following description. It is to be distinctly understood, however, that I do not wish to be limited to the exact structure herein disclosed, but intend to include as part of my invention all such changes and modifications as would occur to those skilled in the art and fall within the scope of the appended claims.

30 In the accompanying drawing, wherein a preferred embodiment of my invention is shown for the purpose of illustration, my improved surgical support is shown in an extended position with the outside of the garment presented to view.

35 My invention is especially applicable to persons having prominent iliac crests suffering from visceroptosis resulting from the disappearance of the fatty tissues of the abdomen which normally supports the organs in proper position. In such 40 cases, it is necessary to gravitate the organs up into their normal position and then occupy from without the region from which the fatty tissues have disappeared. This is accomplished in my improved surgical support by anchoring an occupancy surface closely against the abdominal wall with the wearer in a Trendelenberg position. The occupancy surface is carried within the plane of the iliac crests by locating the retaining side sections for the occupancy surface above and 45 below the projection of the ilia and removing all iliac crest pressure or interference by providing a hood portion defining the contour of the ilium. Preferably, the direction of the warp and weft threads from which the hoods are fabricated is such, relative to the direct pull upon the

retaining sections, that the warp and weft threads are "racked" to lend a decided degree of elasticity to the hood to further relieve any iliac crest pressure or interference in the operation of the occupancy surface.

5 Having specific reference to the drawing, my improved surgical support comprises an occupancy surface 1 of pliable woven material preferably stiffened by longitudinally extending stays 2. Hooks 3 or the like cooperate with eyes 4 to provide quick attachment means. A triangular like side retaining section 5 is secured to the occupancy surface 1 along the line 6. A lower side section 7 is secured to the upper section 5 along the line 8 constituting the hypotenuse 15 of the section 5. The location of the line 8 in the garment and the construction of the sections 5 and 7 are highly important. The upper and lower sections 5—7, as shown in the drawing, are secured together along line 8 which is positioned over the iliac crest and curves downwardly conforming approximately to the anterior superior spine. The curvature of section 5 along the line 8 is less than that of section 7, prior to securing the two sections together, with the result that a fullness constituting a hood-like portion is provided. Preferably, the differentiation in curvature is greatest over the iliac crest. In the drawing, the broken lines in sections 5—7 20 designate the direction of the warp or weft threads as the case may be. It is to be noted that the threads, which may be termed the warp threads, are parallel to the line 6 along which section 5 is secured to the occupancy surface 1. This is for the purpose of effecting a uniform 25 application of retaining force to the surface. The warp threads of section 7 are located in the garment at an angle to the line 6. As shown, the direction of the warp in section 5 is uniformly altered until it is substantially parallel with the warps in section 7 in the locality of the iliac crest as at 9. It is particularly in the locality 30 that a lateral adjustment of the garment to position the surface 1 results in a "racking" or movement of the interwoven warp and weft 35 threads out of the usual right angle position. This "racking" action increases the elasticity of the hood portions and lends considerable flexibility to the locality of maximum fullness with the result that the application of retainer forces 40 upon the occupancy surface 1 from above and below the iliac crests is rendered increasingly 45 freer from iliac crest pressure or interference.

45 The occupancy surface 1 is positioned, in part, within the iliac crests of the wearer, through re- 50

taining sections 10 superimposed upon the sections 5—7 and secured to the surface 1 along the line 6. The sections 10 are substantially unyielding in their retaining action upon the surface 5 1 as distinguished from the flexible and elastic action in the locality 9 of the hip crest and in a plane therethrough parallel with the retaining sections. This construction permits a rearward adjustment of the sections 10, through tightening 10 means located in laced rear sections 11—12, to anchor the garment below the iliac crests and prevent the same from rising thereover while worn; and what is more important, the flexibility of the hood formed along the line 8 relieves the 15 garment from iliac crest pressure and interference and the retaining sections 10 position the occupancy surface 1 well within the iliac crests and into contact with the abnormal abdominal wall in a manner never before accomplished. It 20 eliminates in a great many cases the necessity of employing the usual occupancy pad and in severe cases limits the thickness of such pads to a minimum.

Preferably, the tightening means located in the 25 rear sections 11—12 consist in fabric strips 13 secured to the sections 10 at 14 and passed through adjustment buckles 15 to present forwardly extending portions 16, which are drawn forward to effect a "block and tackle" drawing in action 30 upon the rear sections 11—12, through laces 17 operatively connected with the sections 11—12 and the buckles 15 in a well known manner. It is to be noted that the entire retaining force, effected by an inwardly adjustment of the sections 35 11—12 and transmitted to the occupancy surface 1 through the sections 10, is applied well below the iliac crests. This construction materially assists in providing a garment which will not raise over the hips of the wearer and as 40 the retaining force is below the iliac crests and free from interference therefrom, the occupancy surface 1 is carried further within the ilium.

For positioning the upper portion of the occupancy surface 1, straps 18 are secured to the sections 45 5 and pass through buckles 19 to provide forwardly extended portion 20. Laces 21 coact with the upper portion of the rear sections 11—12 and buckles 19 in a manner similar to the laces 17 and buckles 15 herebefore described. In the 50 upper adjustment the retaining force upon the occupancy surface is applied through the upper portion of the sections 5 well above the locality 9. Thus, as in the lower adjustment, all iliac crest interference is avoided by application of the retaining forces to one side of the ilium.

Obviously, other well known types of adjustments may be employed in lieu of those illustrated with varying degree of success. The essence of the present invention does not lie in any 60 particular type of adjustment but resides in positioning and retaining an occupancy surface within the ilium by providing a garment having upper and lower side sections through which the retaining forces are applied to the occupancy surface with an intermediate section in the locality of the ilium which is hood-like and capable of considerable flexibility for removing all iliac crests, interference or pressure from the upper and lower side sections.

To apply the garment the wearer will preferably take the Trendelenberg position and will pass the same under the back securing the fasteners 3—4. Due to the position taken the ptozed 70 organs will assume their normal position and upon drawing forward the strap portions 16—20

the occupancy surface 1 will be drawn into the abdomen, well within the ilia, to provide a supporting shelf for the organs by occupying from without that which is normally occupied by tissues, the dissipation of which has resulted in a 5 ptozed condition.

Having thus described my invention, what I claim and desire to protect by Letters Patent is:

1. An abdominal support for positioning ptozed organs comprising a front occupancy surface 10 adapted to be positioned against the abdominal wall and within the ilia; upper fabric retaining side sections secured to each side of said surface, one side of said sections being curvilinear and located approximately over the iliac crest and 15 following anterior superior spine when upon the wearer; lower fabric side sections having curvilinear upper edges secured to said first curvilinear edges, said upper edges being of the greatest curvilinearity to provide pressure releasing localities over the iliac crests; lower retaining side sections superimposed upon said lower side sections and secured to each side of the lower portion of said surface; rear sections having upper and lower adjustably laced portions; upper and 25 lower adjustment straps coacting with said portions and secured to said upper and lower side retaining sections above and below the iliac crests for anchoring said surface within the ilia; said pressure releasing localities enabling said 30 surface to be retained in position free from iliac crest pressure or interference.

2. An abdominal support as characterized by claim 1, the direction of the warp and weft threads along the joined curvilinear edges being 35 angularly positioned relative to the direction of adjustment.

3. An abdominal support for positioning ptozed organs comprising a front occupancy surface 40 adapted to be positioned against the abdominal wall and within the ilia; upper retaining side sections secured to each side of said surface, one side of said sections being curvilinear and located directly over the iliac crests when upon the wearer; lower side sections having curvilinear 45 upper edges secured to said first curvilinear edges, said upper edges being of the greatest curvilinearity to provide pressure releasing localities over the iliac crests; rear sections having adjustable laced portions lower retaining side sections superimposed upon said lower side sections and secured to each side of the lower portions of said adjustable laced portions; upper and lower 50 adjustment straps coacting with said laced portions and secured to said upper and lower side retaining sections above and below the iliac crests for anchoring said surface within the ilia; said pressure releasing localities enabling said 55 surface to be retained in position free from iliac crest pressure or interference.

4. An abdominal support for positioning ptozed organs comprising a front occupancy surface 60 adapted to be positioned against the abdominal wall and within the ilia; upper fabric triangle-like side sections secured along one side to each side of said surface, the hypotenuse of said sections being curvilinear and extending from adjacent the lower portion of said surface upwardly and outwardly over the iliac crests; lower 65 fabric sections having curvilinear edges secured to said first curvilinear edges, the curvilinearity of said second edges being the greatest to effect a hood in the locality of the iliac crests; independently adjustable means secured to said upper and lower sections above and below the iliac 70 75

crest to locate and retain said surface in position, said surface being positioned within the ilia free from iliac crest pressure or interference.

5. An abdominal support as characterized by
5 claim 4, the direction of the warp and weft
threads along the joined curvilinear edges in the
locality of the iliac crests being angularly posi-
tioned relative to the direction of adjustment.

6. An abdominal support for positioning pto-
10 organs comprising a front occupancy surface
adapted to be positioned against the abdominal
wall and within the ilia to provide a supporting
shelf for the organs by occupying from without
15 that which is normally occupied from within
by tissues, means attached to opposite sides
of the lower portion of said occupancy surface
through which a drawing up action of the gar-
ment is applied to exert a pressure upon said
occupancy surface for positioning and retaining
20 the same within the ilia, said drawing up ac-
tion through said means being laterally of the
body of the wearer and localized below the iliac
crests, portions of the garment in the locality of
25 the iliac crests being fulled to provide pressure
releasing areas obviating pressure or interfer-
ence by said crests to the positioning of said sur-
face within the ilia through said means, addition-
al means attached to opposite sides of the
30 upper portion of said occupancy surface for re-
taining the same in position, said last mentioned
means being effective laterally of the body of the
wearer and above said iliac crests, and adjust-
ment means for exerting a drawing up action
35 through said first means for positioning and re-
taining said occupancy surface within the ilia.

7. An abdominal support for positioning pto-
40 organs comprising a front occupancy surface
adapted to be positioned against the abdominal
wall and within the ilia to provide a support-
ing shelf for the organs by occupying from with-

out that which is normally occupied from within
by tissues, sections in said garment in the local-
ity of the anterior superior spine being attached
to opposite sides of said occupancy surface, parts
of said sections over the iliac crests being fulled 5
to provide pressure releasing area obviating pres-
sure or interference by said crests to the posi-
tioning of said surface within the ilia through
a drawing up action of the garment, adjustable
10 laced rear sections attached to said first men-
tioned sections, means through which the drawing
up of said laced sections is transmitted laterally
of the body of the wearer and is localized below
the iliac crests for positioning and retaining said
15 occupancy surface within the ilia, said means being
operatively connected with the lower por-
tion of said occupancy surface.

8. An abdominal support for positioning pto-
10 organs comprising a front occupancy surface
adapted to be positioned against the abdominal
wall and within the ilia to provide a supporting
shelf for the organs by occupying from without
15 that which is normally occupied from within by
tissues, sections in said garment in the locality
of the anterior spine being attached to opposite 20
sides of said occupancy surface, parts of said sec-
tions over the iliac crests being provided with
means to afford pressure relieving surfaces ob-
viating pressure or interference by said crests
25 to positioning said occupancy surface within the
ilia through a drawing up action of the garment,
adjustable laced rear sections attached to said
first mentioned sections, means through which
the drawing up of said laced sections is trans-
30 mitted laterally of the body of the wearer and
is localized below the iliac crests for position-
ing and retaining said occupancy surface within
the ilia, said means being operatively connected
35 with the lower portion of said occupancy surface.
